UNITED STATES PATENT OFFICE

2,528,504

ACCELERATING AND BRAKING CONTROL
SYSTEM

Donald E. Findley, Alfalfa County, Okla.

Application June 10, 1948, Serial No. 32,250

1 Claim. (Cl. 318—274)

(Granted under the act of March 3, 1883, as
amended April 30, 1928; 370 O. G. 757)

1

This invention relates to a rotary antenna speed control system and more particularly to a system for controlling the speed of antenna electric motors of the direct current type.

An antenna as used with a radar sending and receiving set is required to be revolved about its axis so as to scan an area for radar signals, and so that the direction of said signal may be determined. As the direction is approached at which the maximum signal strength is received by the radar set, it becomes desirable to slow down the R. P. M. of the said antenna, so as not to overrun this point. This retardation is accomplished by introducing resistance in series with the armature winding of the driving motor which may, for instance, be revolving the said radar antenna at a speed of approximately 6 R. P. M., and so reduce this speed to 2.5 R. P. M. As this resistance is cut in by a relay switch, a second relay switch cuts in a second resistance in the armature circuit in such a manner as to effect a braking action on the speed of rotation of the armature and thereby reduce the speed more rapidly. As the armature speed drops, the voltage in the armature circuit drops and the second relay becomes deenergized to open the second resistance circuit and the speed of the armature shaft becomes constant, at a controlled low speed, maintained constant at any desired R. P. M. by means of said first resistance.

The principal object of this invention is the provision of a speed control circuit for slowing down the speed of rotation of a radar antenna.

Another object of this invention is to provide a control circuit for slowing down the rotation of an antenna for a fraction of a scan to prevent a target from appearing repeatedly in the nulls of the antenna pattern.

A further object of this invention is to change the speed of a D. C. electric motor used for the rotation of an antenna by the introduction of a resistance in series with said motor's armature circuit.

A still further object of this invention is to introduce a second resistance in said armature circuit, which will set up a braking force to quickly retard the rotation of said armature to some predetermined speed of rotation.

A final object of this invention is to have an adjustable potentiometer in a D. C. motor armature circuit, so that a selective low speed of said motor can be maintained after a braking action has been released.

These and other objects of this invention and the various features and details of the construction, operation and use thereof, are hereinafter

2

more fully set forth and described with reference to the accompanying drawing, in which:

The figure shown is a diagrammatic view of the electrical circuits and connections comprising this invention.

Referring now to the drawing, numeral 1 designates the armature of the D. C. motor which revolves the antenna (not shown), and 2 designates a terminal block for connecting the various 10 circuits involved. Switch 3 connects the terminal block 2 to the positive side of the power source, wires 4 connect to the two armature brushes and wire 5 connects the terminal block 2 through an antenna control switch (not shown) to the negative side of the power source. Wire 6 connects terminal block 2 through the series field winding of the motor to the positive side of the power source. Wire 7 connects switch 3 through terminal block 2 to one end of a relay 8 operating switch 15; and from the other end of said relay 8 a wire 9 connects to the negative side of the power source through terminal block 2 and wire 5.

A relay 10 is connected at one end to one of the wires 4 through terminal block 2 and at the 25 other end to normally open stationary contact 15 of relay 8 through variable resistance 13 and wire 14. Resistance 12 is connected at one end to the first-mentioned end of relay 10 and at the other end to the other normally open stationary contact of relay 8 through the normally open contacts 11 of relay 10 and through lead 18. A variable resistor 17 is connected at one end through lead 19 to the other of the wires 4 and at the other end through wire 16 to one normally closed 35 contact of relay 8, said contact being connected to wire 6 at the terminal block 2 by means of wire 21. The movable contacts of relay 8 are connected together and to said one end of resistor 17 by lead 20.

In operation, with switch 3 open, a circuit is completed from the positive side of the power source through the series field winding, wire 6, wire 21, the closed contacts of relay 8, wires 20 and 19, upper wire 4 and the armature 1 to the 40 negative side of the source and the motor operates in a normal manner. When it is desired to decrease the speed of the motor switch 3 is closed thereby energizing relay 8 through leads 5, 7 and 9. When relay 8 is energized the series circuit 45 through the armature 1 and the series field winding is broken, and a new circuit, including armature 1, upper wire 4, wire 19, variable resistance 17, wire 16, wire 21, wire 6 and the series field winding, is completed thereby connecting resistance 17 in series with armature 1.

Furthermore, when relay 8 is energized, relay

10 becomes energized, closing contacts 11 and connecting resistance 12 in parallel with the armature across wires 4 thereby producing a braking action on the rotation of said armature so as to rapidly reduce its speed. As the speed of armature 1 drops, the voltage across relay 10 drops until the relay 10 is deenergized and contacts 11 open. After this braking action is removed the slow speed is then controlled by resistor 17. Resistance 13 and relay 10 are across the armature at all times during the armature's slow speed operation and the length of time for the operation of the electric brake (resistance 12) depends, therefore, on the adjustment of resistance 13. It was found that with the slow speed set forth above, the braking action caused the antenna to stop and reverse, thereby making sector scan possible.

While a particular embodiment of this invention has been illustrated and described herein, it is not intended that this invention be limited to such disclosure, and changes and modifications may be made and incorporated within the scope of the claim.

The invention described herein may be manufactured and used by or for the Government of the United States of America for governmental

purposes without the payment of any royalties thereon or therefor.

I claim:

5 A speed control system for an electric motor having an armature, said system comprising: a resistive element; first relay means for connecting said element across said armature; a variable impedance; second relay means selectively energizable for simultaneously inserting said impedance in series with said armature and connecting said first relay means across said armature to thereby energize said first relay means, said first relay means being deactivated when the speed of said armature decreases to a predetermined value; 10 and adjusting means connected to said first relay means to control the point of deactivation thereof.
